Application August 26, 1929. Serial No. 388,289

19 Claims. (Cl. 179—171)

REISSUED

DEC 5 1939

The invention relates to the use of iron or other magnetic materials in radio-frequency and other alternating current circuits. More particularly, the present invention contemplates the use of such materials in tuned radio-frequency amplifying circuits, although the particular new instrumentalities to be described and claimed are not limited in their advantageous application to this particular class of apparatus.

10 As is well understood in the radio art, a tuned radio-frequency amplifying circuit consists essentially of a relay device such as a thermionic amplifying tube, and an electrically connected resonant circuit consisting of inductance and capacity. This resonant circuit is the portion of the radio-amplifying circuit in which the property of selectivity resides, and it may therefore be referred to as the selective circuit, as distinguished from the complete amplifying circuit including

20 the tube or relay. Hitherto, many attempts were made to employ iron cores in the transformers used in radio frequency, but owing to great losses introduced by the iron as then employed, efficiency was generally impaired, so that air-core coils and transformers are now exclusively used in the cases where relatively high-frequency oscillations, either modulated or not by voice frequencies, are to be selected and amplified by thermionic tubes

30 and associated circuits. The invention will be better understood if reference is made to the accompanying drawings where

Figure 1 represents a general circuit employing 35 thermionic tubes and embodying the present invention;

Figure 2 is a diagram showing the amplification of a single stage of such a system;

Figure 3 is a diagram showing the resistance 40 variations of different transformers or coils;

Figures 4, 5, 6, 7 show various modifications of the present invention;

Figure 8 shows one application of the present 45 invention;

Figure 9 shows the amplification curve of one stage of the circuit, of Figure 8;

Figures 10, 11, 12 and 13 show selectivity curves of amplifiers of various designs, and

Figures 14 and 15 show modifications of the 50 invention.

Figure 16 shows a tuning device including correlated elements.

It is an usual practice to employ several stages of radio-frequency amplifiers in cascade, such as 55 shown on Figure 1, having variable inductances

or capacities, or both, in tuning circuits, so as to cover a certain band of frequencies, say from 1,500 to 550 kilocycles. Such a wide range of frequencies renders those amplifying circuits inefficient and different in operation at different frequencies. 60

It is the object of the present invention to improve fidelity, selectivity and efficiency and to secure uniformity of amplification.

Mathematical analysis (Victor G. Smith, Proc. I. R. E. vol. 15, No. 6, June 1927) shows that 65 amplification of tuned radio-frequency circuits is represented by the ratio of output to input voltages:

$$\frac{V_o}{V_i} = \frac{1}{2} \frac{\mu}{\sqrt{R_1} \sqrt{R_2}} \cdot \frac{\omega L_2}{\omega^2} \text{ and } M^2 = \frac{Z_1 Z_2}{\omega^2}, \text{ where } \omega = 2\pi f, \quad 70$$

providing the circuit is tuned to the resonance, and optimum coupling between primary and secondary circuits is obtained for every given frequency. These formulae prove that, in the case of 75 fixed value of inductance L_2 in order to keep the amplification constant, the resistance R_2 of the tuned circuit, which is chiefly composed of the coil's resistance, should change proportionately to the square of the frequency. 80

In the case of a fixed value of mutual inductance, M , the amplification decreases with increase of tuning capacity as represented by the curve a of Figure 2, wherein mutual inductance is adjusted for the high-frequency end of the 85 frequency band. Mutual inductance can be chosen to be at the optimum value somewhere in the middle of the frequency band as represented by the curve b of said figure. In this case, the circuits, being over-coupled at high 90 frequency and under-coupled at low frequency, produce non-uniform amplification. The above formulae also prove that in order to keep the mutual inductance at its optimum value throughout the frequency band, the resistance R_2 should 95 be so changed as still to be proportional to the square of the frequency.

Actual measurements of the resistance of an air coil or transformer, show that the coil changes its resistance with frequency changes, but not as 100 much as would be required to keep the amplification constant and the mutual inductance at optimum. Curve a of Figure 3, shows the resistance for a certain air coil, measured at different frequencies, while curve b represents the 105 resistance required to maintain said resistance proportional to the square of frequency.

One object of this invention is to provide radio-frequency circuits with transformers and coils which will not be subject to the described de- 110

ficiencies of air coils, to thereby attain even amplification with optimum mutual inductance. It has been found that the use of finely-powdered iron in the field of an air coil, will change the 5 variation of the resistance of the coil relatively to variations in frequency.

A low-resistance air coil was chosen, and its inductance was materially augmented by powdered iron disposed within said coil. The actual 10 measurements of resistance throughout the entire range of frequencies utilized, shown by the curve b of Figure 3, indicate that the resistance changed approximately nine times while the frequency changed approximately three times. Numerous 15 measurements have verified the fact that the resistance of iron-core coils remains proportional to the square of the frequency, despite frequency changes.

Transformers having powdered iron cores, were 20 connected with thermionic tubes and other elements of the circuit of Figure 1, and it was found that the amplification curve remained substantially even throughout the entire range of frequencies, as represented by the curve c of Figure 2. Thus, a close agreement with theoretical 25 considerations was established, that is to say, that when resistance varies as the square of the frequency, the amplification of a tuned circuit remains constant and the mutual inductance adjusts itself to optimum value.

The resistances of transformers having powdered-iron cores, being extremely small at 550 k. c. and the lower frequencies, it is possible to build transformers and coils designed for those 30 low frequencies having an L/R ratio much greater than is practical if ordinary air coils are employed. Furthermore, it is possible to reduce the windings and thereby minimize the size of radio-frequency transformers, thus effectuating 35 a saving of space.

There may be several embodiments of my iron-core coils and transformers, the simplest embodiment being shown in Figure 4 wherein primary and secondary coils 1, 2 are wound on an insulated tube 3, and powdered iron 4 is packed inside 40 the tube 3, and the ends 5 of the tube are sealed.

Figure 5 shows schematically a binocular coil 6 wound on insulated tubes 7, portions 8 of the powdered iron being separated by thin paper discs 50 9, to prevent readjustment of its particles and consequent packing and slight change in inductance.

Iron cores can also be made by mixing various adhesive and insulating compounds with powdered iron, and giving these cores the desired 55 shape with or without pressure. Also, certain other insulators, such as wax, paraffine and mineral oils, may be used. Substances when melted and mixed with iron particles, while hot manifest 60 very small losses but, when cold and solidified, increase the conductivity of iron cores thousands of times and establish easy paths for eddy currents at high frequencies, resulting in a considerable increase in radio-frequency resistance of 65 the coils equipped with such cores.

However, a coil having either a melted or an 70 unmelted core of wax, without powdered iron, developed substantially no resistance in the coil, while, when powdered iron was mixed with the wax of said core, the resistance in said core was 75 5 ohms, if the wax was melted, and was 50 ohms, if the wax was solidified. Also, when the core comprised the same mass and quality of powdered iron the resistance of the coil was 5 ohms.

Other insulators preferably of elastic nature,

such as rubber, natural and synthetic gums and certain varnishes mixed with iron and pressed together, will maintain insulating films between the iron particles and, therefore, reduce resultant radio-frequency losses.

The definition "iron" used in the specification should be applied to any other metal or alloy having magnetic properties, such as silicon-iron, permalloy and nickel-iron. Various powdered metals were tested for radio-frequency transformers and inductances, and it was found that for the most satisfactory results iron reduced by hydrogen, the particles of which had been sifted through a screen of 300 meshes to the inch, should be used for frequencies between 1500 to 1000 k. c., but that powders containing coarser particles may be used for frequencies below 1000 k. c., and also that the fineness and the force of compression govern the radio-frequency resistance of the coil. Iron produced by hydrogen in the ordinary way contains particles of various sizes some of which may be too large for use in the production of cores suitable for use in radio frequency circuits. It is, therefore, necessary to eliminate the largest particles. The insulating 100 coat of oxide usually present on the surfaces of iron particles, helps to reduce eddy-current losses. When silicon iron powder is used it is practical to chemically treat the powder with a phosphoric acid solution which creates an insulating film. 105

When, in this specification, "powdered iron" is referred to, I mean either incoherent masses of finely-divided iron, or masses of finely-divided iron compressed into bodies in which the individual particles are held together by an insulating 110 binder, but the degree of compression should not be so great as to cause the particles of powdered iron to touch each other and thus exclude the insulating material which should separate them.

To obtain maximum gain in inductance, thus 115 due to the iron cores, the length of a coil should be preferably twice its diameter, and the wire should be space-wound, such arrangement being shown in Figure 6, wherein 10 indicates a space-wound wire, and 11 indicates the powdered iron 120 core. The inductance may be further augmented if the iron core extends around the outside of the coil in the form of cylinder 12. Such arrangement of iron completely closes the magnetic lines around the coil, forming an astatic coil. 125 When iron cores are employed in the coils of the closed or semi-closed magnetic field type, the original astatic properties of such coils are greatly enhanced. While the powdered-iron core substantially doubles the individual primary and 130 secondary inductances, it increases the mutual inductance between the windings four or five times.

This phenomenon is especially advantageous 135 when a very tight coupling is required, or when long solenoids are employed for transformation.

Another object of the present invention is to tune a radio-frequency circuit in a new, simple and efficient manner, a movable powdered iron core disposed in the field of a coil being employed 140 for tuning purposes. Depending on the amount of the iron powder inserted in the form of a core, the self-inductance of a coil may be increased four and even six times with a resulting increase 145 in radio-frequency resistance.

Figure 7 shows a binocular transformer 13, having a core 14 which can be moved in and out to obtain variations of self-inductance and mutual inductance. This device is capable of tuning the 150

circuit to a desired frequency when connected with tubes and associated circuits such as shown in Figure 1, or such as are shown in Figure 8 wherein a radio-frequency choke amplifier is represented. In this figure are shown thermionic tubes, 15 and 16, acting as radio-frequency amplifiers, a detector tube 17, choke coils 18 having powdered-iron movable cores 19, suitable resistances 20, coupling condensers 21, a telephonic receiver 22, and a plate battery 23, filament-heating means being omitted for simplicity. In this system it is possible to work the amplifier at its full efficiency throughout a given range of frequencies by moving iron cores inward or outward.

15 The amplification per stage is shown by curve *a* of Figure 9. Core movements can be made simultaneous with the movements of the input selector, which selector is usual to secure the necessary selectivity for wave lengths of different

20 broadcasting stations.

When the selecting of a signal accompanies amplification, as in the cascade radio-frequency amplifier shown in Figure 1, the ability to select is called "selectivity" of tuned circuits. In an ordinary air-core transformer associated with a thermionic amplifier, selectivity varies with frequency. Actual measurements, made for a circuit having L-180 microhenrys variable capacity from 10 to 500 micro-microfarads and total resistance of the circuit varying from 7 to 4 ohms, are shown in Figure 10, wherein, the amplification is plotted against kilocycles off of resonance. Curve *a* is taken at a frequency of 1400 k. c., curve *b* at 1000 k. c., and curve *c* at 600 k. c. Vertical lines *d* and *g* are drawn at 10 k. c. off of resonance and represent interfering adjacent stations. Curve *a* shows inadequate selectivity due to high resistance of the circuit and to lack of capacity. As frequency decreases, the resistance decreases the result being sharpening of the curves *b* and *c* representing selectivity. By decreasing the inductance and the losses in the circuit and increasing the initial amount of tuning capacity, it is possible to obtain sharper curves as shown in Figure 11. These three curves *a*, *b* and *c*, represent a very satisfactory selectivity, the amplitudes, as shown, being different because of fixed mutual inductance. The curves of Figure 12 represent the selectivity obtained from a transformer, equipped with a fixed powdered-iron core as hereinbefore described.

As the radio frequency signal is usually modulated by voice frequencies, three frequencies f_0 , $f_0 - f_v$, and $f_0 + f_v$, where f_0 is carrier frequency, f_v is voice frequency, have to be passed through a selective circuit with substantially equal intensities in order to avoid distortion. To secure intelligible audio signals, it is usual to modulate carrier frequency with voice frequencies ranging from 0 to 5000 cycles, and, therefore, selective circuits should be capable of passing a band of frequencies 10 kilocycles wide, to obtain the fidelity of reproduction. Two vertical dotted lines *h* and *k* in Figures 10, 11 and 12, represent the limits of audio-frequency modulations to be passed through each selective circuit. Referring back to Figure 10, one can easily perceive that curve *a* shows almost perfect fidelity, curve *b* shows slightly distorted fidelity, the extreme side bands being attenuated about 15% as compared with carrier frequency, and curve *c* shows 50% attenuation of its side bands and, therefore, introduces distortion. Curve *a* of Figure 11 shows good fidelity, but curves *b* and *c* show distortion.

Comparison of these curves with curves obtained by the use of powdered-iron core transformers, shows that all of the curves of Figure 12 have very good fidelity, and poor selectivity. It is therefore essential for good selectivity and fidelity, throughout the entire frequency range, to combine the selectivity of a low-loss high-capacity circuit at high frequency with the selectivity and fidelity obtained by powdered-iron cores at low frequency.

An amplifier was constructed with low-loss, low-inductance coils and a movable powdered-iron core and included in the circuit shown by Figure 1. Tuned to high-frequency signals, such as 1500-1200 k. c., said core was entirely withdrawn and the amplifier then developed the characteristics of the curve *a* of Figure 11. From any high-frequency between 1500 and 1200 k. c., to 550 k. c., said core was gradually moved inside the coil, and, due to increases of self and mutual inductances and of radio-frequency resistance, the curves became broad as shown by curves *b* and *c* of Figure 12. The resultant group of curves, taken at three different frequencies, is separately represented in Figure 13 and shows substantially the same selectivity and fidelity throughout the entire range of frequencies.

As it is customary to express the selective properties in terms of band widths in kilocycles at half amplitude, I have chosen to call this quantity the "selectance" and have used this word in this sense in the appended claims. As determined from Figure 13, the selectance is of the order of 30 k. c., slightly varying at three investigated frequencies. Theoretical analysis of a resonant circuit indicates that selectance expressed in band width is directly proportional to

$$\frac{R}{L}$$

115

where *R* and *L* are, respectively, resistance and inductance of the circuit, selectance being somewhat impaired by the effects of the plate electrode of an associated thermionic amplifier, should an amplifying stage be employed. The fact that the selectances are substantially equal at three investigated frequencies, indicates that

$$\frac{R}{L}$$

124

was kept substantially constant.

The equal amplifications represented in Figure 13 at three different frequencies, are easily explained if reference is made to Figure 14 wherein one amplifying stage is shown with a tuned circuit 24 directly connected with the plate of a thermionic amplifier, said circuit consisting of an inductance made variable by an iron core 25 and an adjustable condenser 26, the output voltage of said amplifier being fed to a succeeding thermionic amplifier through a condenser 28 and a grid resistance 27. Figure 15 shows essentially the same circuit 24 at 29, with the exception that output voltage is fed through an additional winding 30 unitarily coupled, to the inductance of the tuned circuit 29.

The amplification may be theoretically expressed as

$$\frac{V_o}{V_i} = \mu \frac{R_o}{R_i + R_o}$$

145

where μ is the amplification factor and R_i the plate resistance of the thermionic amplifier, and

150

R_o the dynamic resistance of the circuit 24, in resonance equal to

$$\frac{L}{RC}$$

5 of the circuit. As the inductance L is varied for tuning, the resistance R of the circuit, resulting from the coil resistance and iron core losses, should proportionately vary so as to maintain

10 $\frac{L}{R}$,

with the resultant R_o and

15 $\frac{V_o}{V_i}$

constant.

20 In case of simultaneous variation of capacity and inductance, the amplification of such a circuit can be represented by the above formulae modified as follows:

$$\frac{V_o}{V_i} = \frac{1}{2} \frac{\mu}{\sqrt{R_1 C_2}} \sqrt{\frac{L_2}{R_2 C_2}} \text{ and } M^2 = \frac{Z_1 Z_2}{\omega^2}, \text{ where } \omega = 2\pi f,$$

25 and where the ratio

$$\frac{L_2}{R_2 C_2}$$

30 is dynamic resistance of circuit in resonance. In addition to the change of value of L_2 and C_2 , R_2 is also varied by the movement of the iron core. By properly designing the low-loss coils, and properly choosing the quantity, fineness of and pressure on the iron, as well as adjusting the 35 movement of the iron core in conjunction with other tuning elements, amplification may be kept constant.

40 Using loose coupling between the primary and secondary circuits, it was found favorable to vary the mutual inductance to a very large extent, so that at high frequencies the primary and secondary circuits were under-coupled while at low frequencies they were over-coupled, these variations being produced automatically by the said 45 movements of the iron core.

45 When movable iron cores are used for tuning purposes in conjunction with other variable devices, such as variable condensers, variable inductances, variometers and the like, the movements of iron cores should be correlated with the movements of said variable devices. It is preferable to so adjust the cores that, at the higher frequencies, the iron is kept away from the coils. As the frequency decreases, the iron cores should be gradually inserted into the coils, with a constant or an accelerated speed, depending on the 55 design of other tuning devices employed.

50 Figure 16 shows a selective device embodying a movable iron-core which can be used in connection with amplifying circuits, such as shown in Figures 1, 14 and 15. A variable condenser 31 having stationary plates 32 and rotary plates 33, carries a grooved cam 34 firmly connected with the shaft 35. A lever 36, engaging the cam groove, 60 actuates a vertical rod 37 to which a powdered-iron core 38 is fixed. A transformer 39, which may be an impedance coil, telescopically receives said core 38. When the condenser plates are 65 rotated for tuning purposes, the cam 34, its lever 36 and the vertical rod 37 are set in motion, so that the core 38 travels inward and outward relatively to the coil 39. When the condenser plates 33, are out, the core 38 is all the way out, which position corresponds to a higher-frequency 70 limit of the circuit. When the plates 33 are in, 75

the core 38 is in the coil and this position corresponds to a lower-frequency limit. The movements of the core in relation to the rotation of the condenser plates is governed by the curvature of the cam 34. It is possible to move the core 80 38 proportionally to the angular movement of the rotary plates, in which case the condenser plates may be so shaped as to give the desired capacity variations. However, it is preferable to employ semi-circular plates producing straight-line capacity variations, and to so choose the curvature of the cam 34 that the speed of the core will be accelerated relatively to that of the rotary plates 33 of the condenser. This train of elements admits of a slow movement of the core 85 38 when said plates are having their initial angular motion, but causes a gradual acceleration of the speed of the core 38 which reaches its maximum when the plates 32 and 33 coincide. Such combination of semi-circular plates with a progressively moving core, effectuates the production of equally wide frequency channels throughout the entire range of the selector.

90 Having thus described my invention, what I claim is:

100 1. A radio-frequency amplifying circuit including a relay device and a selective circuit electrically connected to the output terminals of said relay device and having an inductance coil, an external capacity across said coil, and a compressed magnetic body disposed in the field of said coil, said body having insulated magnetic particles and being of such characteristic that the amplifying circuit has selective properties substantially the same as when said magnetic body is withdrawn.

105 2. A radio-frequency amplifying circuit including a relay device and a selective circuit electrically connected to the output terminals of said relay device and having an inductance coil, an external capacity across said coil, and a compressed magnetic body disposed in the field of said coil, said body having insulated magnetic particles of such fineness that said amplifying circuit has selective properties substantially the same as when said magnetic body is withdrawn.

110 3. A radio-frequency amplifying circuit including a relay device and a selective circuit electrically connected to the output terminals of said relay device and having an inductance coil, an external capacity across said coil, and a compressed magnetic body disposed in the field of said coil, said body being of a closed magnetic type and having insulated magnetic particles to maintain the selectance of said amplifying circuit at the 115 desired value.

120 4. A radio-frequency amplifier including a relay device and a selective circuit electrically connected to the output terminals of said relay device and having an inductance coil, an external capacity across said coil, and a magnetic body disposed in the field of said coil, said body being compressed and having particles insulated by an elastic substance and being movable relatively to said coil to vary the period of said selective circuit 125 while retaining the desired amplification.

130 5. A radio-frequency amplifier including a relay device and a selective circuit electrically connected to the output terminals of said relay device, said selective circuit having an inductance 135 coil, an external capacity and a compressed magnetic body disposed in the field of said coil, said body having insulated magnetic particles of a size small enough to pass through a screen of 300 meshes per inch and being movable relatively to 140

145

- said coil to vary the period of said selective circuit while retaining the desired amplification.
6. A radio-frequency amplifier including a relay device, a selective circuit, inductively connected through a unitary coupling to the output terminals of said relay device, said selective circuit having an inductance coil, an external capacity and a compressed magnetic body disposed in the field of said coil, said body having insulated magnetic particles and being movable relatively to said coil to vary the period of said selective circuit while retaining the desired amplification. 80
7. A radio-frequency amplifying circuit including a relay device and a selective circuit electrically connected to the output terminals of said relay device, said selective circuit having an inductance coil, an external capacity and a compressed magnetic body disposed in the field of said coil, said body having insulated magnetic particles and being movable relatively to said coil to vary the period of said selective circuit while maintaining the selectance of said amplifying circuit at the desired value. 85
8. A radio-frequency amplifying circuit including a relay device and a selective circuit electrically connected to the output terminals of said relay device, said selective circuit having an inductance coil, an external capacity and a compressed magnetic body disposed in the field of said coil, said body having insulated magnetic particles and being movable relatively to said coil to vary the inductance and the radio-frequency resistance of said selective circuit simultaneously and in the same proportion so as to produce substantially uniform amplification and selectance in said amplifying circuit throughout the range of adjustability. 90
9. A radio-frequency amplifying circuit including a relay device and a selective circuit electrically connected to the output terminals of said relay device, said selective circuit having an inductance coil, an external capacity and a compressed magnetic body disposed in the field of said coil, said body having insulated magnetic particles and being movable relatively to said coil to vary the inductance and the radio-frequency resistance of said selective circuit simultaneously and in the same proportion so as to produce substantially uniform selectance in said amplifying circuit of the order of 30 kilocycles width at half amplitude throughout a frequency range from 550 to 1500 kilocycles. 95
10. A radio-frequency amplifier including a relay device and an inductively coupled selective circuit, having an inductance coil, a variable capacity and a compressed magnetic body movable in the field of said coil, said body having insulated magnetic particles, the movement of said body being correlated with the adjustment of said variable capacity so as to produce substantially uniform amplification throughout the range of adjustability of said amplifier. 100
11. A radio-frequency amplifier including a relay device and an inductively coupled selective circuit, having an inductance coil, a variable capacity and a compressed magnetic body movable in the field of said coil, said body having insulated magnetic particles, the movement of said body being correlated with the adjustment of said variable capacity so as to produce substantially constant effective dynamic resistance between the output terminals of said relay device. 105
12. A radio-frequency amplifier having a relay device, a selective circuit including the secondary coil of a transformer, an external capacity and a compressed magnetic body movable in the field of said coil, said body having insulated magnetic particles, a primary winding of said transformer being connected to the output terminals of said relay device, the movement of said body simultaneously varying the secondary inductance and the mutual inductance of said transformer to tune said amplifier while maintaining the desired amplification. 110
13. A radio-frequency amplifier having a relay device, a selective circuit including a secondary coil of a transformer, a variable capacity and a compressed magnetic body movable in the field of said coil, said body having insulated magnetic particles, a primary winding of said transformer being connected to the output terminals of said relay device, the movement of said body being correlated with the adjustment of said capacity and simultaneously varying the secondary inductance and the mutual inductance of said transformer to produce desired amplification in said amplifier. 115
14. A system including a plurality of radio-frequency amplifying circuits, having selective input and interstage circuits arranged in cascade, said selective circuits each having an inductance coil, an external capacity and a compressed magnetic body disposed in the field of said coil, said body having insulated magnetic particles and being movable relatively to said coil for tuning said system while maintaining the selective properties of said system at the desired values. 120
15. A radio-frequency amplifying circuit including a relay device and a selective circuit electrically connected to the output terminals of said relay device and having a low-loss inductance coil, a capacity across said coil, and a compressed magnetic body disposed in the field of said coil, said body having insulated magnetic particles and being of such characteristic that said amplifying circuit maintains its selective properties substantially the same as when said magnetic body is withdrawn. 125
16. A radio-frequency amplifier including a relay device and a selective circuit electrically connected to the output terminals of said relay device, said selective circuit having a low-loss inductance coil, a capacity across said coil, and a compressed magnetic body disposed in the field of said coil, said body having insulated magnetic particles of size small enough to pass through a screen of 300 meshes per inch and being movable relatively to said coil to vary the period of said selective circuit while retaining the desired amplification. 130
17. A system including a plurality of radio-frequency amplifying circuits, having selective input and interstage circuits arranged in cascade, said selective circuits each having an inductance coil, an external capacity and a compressed magnetic body disposed in the field of said coil, said body having insulated magnetic particles and being movable relatively to said coil for tuning said system while preserving substantially uniform amplifying properties in said system. 135
18. A system including a plurality of radio-frequency amplifying circuits, having selective input and interstage circuits arranged in cascade, said selective circuits each having an inductance coil, an external capacity and a compressed magnetic body disposed in the field of said coil, said body having insulated magnetic particles and being movable relatively to said coil for tuning said system while retaining the desired amplifying properties in said system. 140
19. A system including a plurality of radio-frequency amplifying circuits, having selective input and interstage circuits arranged in cascade, said selective circuits each having an inductance coil, an external capacity and a compressed magnetic body disposed in the field of said coil, said body having insulated magnetic particles and being movable relatively to said coil for tuning said system while retaining the desired amplifying properties in said system. 145
20. A system including a plurality of radio-frequency amplifying circuits, having selective input and interstage circuits arranged in cascade, said selective circuits each having an inductance coil, an external capacity and a compressed magnetic body disposed in the field of said coil, said body having insulated magnetic particles and being movable relatively to said coil for tuning said system while retaining the desired amplifying properties in said system. 150

19. A radio-frequency amplifying circuit including a relay device and at least one selective circuit connected to the output terminals of said relay device and having an inductance coil, a variable capacity and a compressed magnetic body movable in the field of said coil, said body having insulated magnetic particles, and means

whereby the variation of the capacity and the movement of the core vary the period of the selective circuit while maintaining the amplification and selectance at the desired value.
